UNITED STATES PATENT OFFICE

2,201,428

DENTAL AMALGAMATOR

Edward L. Chott, Chicago, Ill., assignor of one-half to Hugo J. Chott, Chicago, Ill.

Application March 16, 1939, Serial No. 262,118

8 Claims. (Cl. 259—72)

This invention relates to amalgamators and more particularly it relates to amalgamators as employed in dental laboratories for amalgamating, for example, mercury and alloys for making fillings. It will be manifest that it is desirable that the amalgamation be very thorough and be done with a minimum of time and labor. I am familiar with devices heretofore provided in the shape of vibrators, for example, and an object of my invention has been to produce an improved amalgamator which will be not merely a vibrator or oscillator. By means of my invention, I have provided means whereby the mortar or capsule holding the ingredients to be amalgamated will have the direction of its axes changed and be moved in every essential way to produce a thorough amalgamation.

By means of my invention, the mortar and ingredients will be moved in a somewhat circular, up and down and side to side motion with the mortar or capsule changing the direction of its axes at each revolution so that the ingredients to be amalgamated will be agitated and shaken in every essential way.

By means of my invention, tests show that an amalgamation that requires 90 seconds at the present time may be produced in 7 seconds, and in addition, an improved amalgamation is produced.

An object, among others, is to provide means for accomplishing the foregoing results which will be simple and relatively inexpensive, easy to assemble and obviate oiling. The elimination of oiling is of considerable importance to dentists as the devices now in use require oiling, which has manifest disadvantages.

Other objects and advantages will appear and be more fully brought out in the following specification, reference being had to the accompanying drawing, wherein:

Fig. 1 is a side view of the device;

Fig. 2 is a plan view of same;

Fig. 3 is a sectional elevation of same taken on the line 3—3 of Fig. 1.

Fig. 4 is a vertical section of part of the device;

Fig. 5 is a plan view of the eccentric bushing in the position shown in Fig. 2;

Fig. 6 is a plan view of same with its position changed 180 degrees;

Fig. 7 is an end view of the eccentric bushing;

Fig. 8 is a view from the opposite end of the bushing;

Fig. 9 is an elevation of a modified form, partly in section;

Fig. 10 is a section of the bushing and motor shaft in the position shown in Fig. 9; and

Fig. 11 is a section of the same with the bushing changed 180 degrees in position.

Referring to the drawing where I have selected preferred forms for purposes of illustrating the principles of my invention, there is shown referring more particularly to Figs. 1-3, base 15 with one or more cushions 16, the base having a circumferential flange 17 and the base being provided with securing holes 18. A motor housing 19 is mounted on the base 15 by suitable means and there is provided therefor a cord 20 having plug 21 for a source of power supply and the motor housing is provided with a switch 22. The motor has the usual rotor shaft 23 with one end provided with threads 24.

Adapted to be mounted upon the threaded end 20 of the shaft 23 is an eccentric bushing 25 particularly illustrated in Figs. 5, 6, 7 and 8. The bushing 25 has a tapered hexagonal flange 26 having an outer face 27 normal to the axis of shaft 23 and an inner face 28 at an intersecting angle to the angle or plane of face 27, or obliquely or diagonally to said axis. The bushing also includes an integral sleeve 29. According to the principles of my invention, I have arranged the structures so that the outer cylindrical surface of the eccentric bushing 25 will be at an acute angle to the axis of the motor shaft 23. I have found it satisfactory to arrange the outer cylindrical surface of the sleeve 29 at an angle of six degrees to the motor shaft 23 although obviously this may be changed as found expedient and a different angle adopted.

In the form which I have shown, the outer surface of the sleeve 29 is at right angles with or normal to the inner face 28 of the flange 26 and at an angle of six degrees with the outer face 27 of the flange 26.

It will be seen particularly from Figs. 5 and 6 that the sleeve is off center or eccentric with respect to the flange 26.

The bushing 25 is provided with a threaded bore 30 which bore, it will be understood, may be at an angle of six degrees with respect to the outer cylindrical surface of the sleeve 29. In this case, it will be seen that motion transmitted from the shaft will have its direction changed in that the surface of the cylindrical sleeve 29 is at an angle of six degrees with respect to the shaft 23.

Mounted eccentrically on the sleeve 29 opposite

to the eccentricity of the bushing 25 is a ball bearing cage 31 having the usual ball bearings, and in turn loosely mounted upon the ball bearing cage is a split collar support 32 having integral ears 33 adapted to be locked together by clamping screw 34 to clamp also one end of a spring 35 therebetween. The other end of the spring extends through an opening 36 in the base 15 and being anchored by means of a pin 37 mounted in the recess 38. The spring keeps the support from turning with the bushing and tends to normally hold the support vertical and absorbs and takes up throw, thrust and vibration.

15 The split collar support 32 has an integral vertical extension 39 supporting a pair of spring arms 40 secured by screws 41 or other suitable means. The spring arms 40 are formed at their upper ends with integral cups 42 of a somewhat 20 semi-spherical form and also grasping projections 43 are formed to facilitate handling of the device.

25 Adapted to be held by the spring arms 40 in the cups 42 is a mortar or capsule 44 consisting of a hollow chambered body 45 provided with a hollow cap 46, the body 45 and cap 46 having preferably rounded semi-spherical ends 47 to register with the cups 42. The roller bearing cage 31 is held on the sleeve 29 by a collar 48. This 30 collar 48 has an inner face 49, an outer face 50, and a bore 51 of the collar which is mounted on the shaft 23. The outer face 50 of the collar 48 is at right angles to the bore 51, but the bore in the form shown is arranged at an angle of six 35 degrees with respect to the inner face 49. The angled inner face 49 registers with the end of the cage 31 and a hexagonal locking cap or cap nut 52 threads on the shaft 23, by which construction the bushing and cage are held properly mounted on the shaft 23.

40 It will be seen from the foregoing that the bushing will revolve within the roller bearing cage and as the high point of the eccentric bushing 25 revolves, it will cause the split collar support 32 to be moved in such a manner that the mortar will be moved in a circular back and forth and up and down and side to side motion with the mortar changing the direction of axes at each revolution. That is, the mortar is oscillated horizontally laterally on a vertical axis, and simultaneously reciprocated or caused to take a swinging motion back and forth with each horizontal lateral oscillation. A particular advantage of this motion is that the substance to be amalgamated is shaken in practically every essential way and more efficiently than the human hand would shake it. It is not merely oscillated about an axis, but is so moved that the mortar changes the direction of axes during every revolution.

45 In Figs. 9, 10 and 11, I have shown a modified form of the device. There is shown a motor 53 with supporting lugs 54, a cord 55 for a source of power supply, a shaft 56 threaded as at 57, an eccentric bushing 58 having a flange 59 and sleeve 60. As shown in Figs. 10 and 11, the bushing 58 has a reduced portion 61 and a threaded stem 62. The bushing has a bore 63 which is off center leading from its flanged end, as clearly shown in said figures. In the form shown, the stem 62 and the cylindrical surface 60 together with the cylindrical surface of the reduced portion 61 are at an angle of six degrees with respect to the shaft 56, the principle being the same as in the case of the connection between the bushing 25 and 70 the shaft 23 of the first form.

75 A hub 64 is provided with a bore 65 and is mounted on the bushing 58. A collar 66 is provided on the stem 62 against the hub 64 and there is also provided upon the stem a washer 67 and a pair of locking nuts 68 clearly shown in Fig. 9. The hub 64 has a vertical integral post 69 having spring arms 70 with spring cups 71 adapted to engage and hold the mortar 44. The vertical post 69 extends through a slotted guide 72 which may be integral with the motor housing, as clearly 10 shown in Fig. 9.

In this form, as in the previous form, it will be seen that the bushing 58 will revolve within the hub 64 and as the high point of the eccentric bushing revolves, it will cause the hub to be 15 moved in such a manner that the mortar will be moved in a circular back and forth and up and down and side to side motion with the mortar changing the direction of its axes at each revolution. It will thus be seen that whereas in the 20 first form, the spring 35 limits the movement of the mortar supporting arms and the supporting split collar support about the bushing, in the second form, the movement of the hub 64 and mortar supporting arms 70 about the bushing or turning 25 therewith is limited by the slotted guide 72 which keeps the arms vertical.

30 It will be understood that while I have stated that I have found that arranging the axis of the cylindrical surfaces of the bushings at an angle of six degrees to the shaft is preferable, this can of course be varied.

The letter A in Fig. 1, referring to the dotted lines, represents the rearmost position of the mortar holding arms and mortar. In this position, 35 the longitudinal axis of the mortar will be at an angle to the motor shaft and in the plane of the motor shaft.

The letter B in Fig. 5 represents the position of the bushing after it has turned at an angle of 90 40 degrees from the position which it would have had with the mortar holding arms in the position of letter A and is the same as the position of the bushing in Fig. 2.

The letter C indicates the position of the mortar and mortar holding arms after the bushing has been moved 90 degrees further in its revolutions or 180 degrees from the dotted line position in Fig. 1 and the mortar arms and mortar and bushing are in the opposite position from that 50 which they occupy in the dotted line position in Fig. 1. This is the foremost position of the mortar holding arms and mortar; that is, the position when they are farthest away from the motor housing or farthest to the right, as shown in 55 Fig. 1.

The letter D in Fig. 6 represents the position of the bushing after the bushing has been further turned 90 degrees from the position shown in Fig. 1 and this position is opposite from the position 60 shown in Figs. 2 and 5.

65 Letter E indicates a point on the axis on the cylinder of the cylindrical surface of the bushing and the bushing turns horizontally on this axis during every revolution.

In this way, as the bushing rotates, the mortar travels in a circular manner from a rearward to a forward position changing or reversing the direction of the axes of the mortar when it travels 70 from a rearward to a forward position and back again as it moves from the forward to the rearward position in its rotary path. In other words, it travels from the rear forwardly and from the forward position to a rear position and from side 75

to side and changes the direction of its axes in each revolution of the bushing.

As shown in Fig. 4, a pestle or pellet 73 is preferably used to disintegrate and amalgamate the ingredients. The operation of the pestle within the mortar will be manifest from the foregoing description. I have found that the use of the pestle assists and speeds up the amalgamation.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. In an amalgamator, a motor, a shaft operated by said motor, a cylindrical bushing eccentrically mounted on said shaft with its longitudinal axis at an acute angle to said shaft, and mortar supporting means loosely mounted on said bushing and extending substantially radially thereto, and means preventing rotation of the mortar supporting means with said shaft.

2. In an amalgamator, a motor driven shaft, mortar supporting means, a mortar supported thereby, and a connection between said shaft and said supporting means for oscillating the mortar on its transverse axis which passes radially through said shaft and simultaneously reciprocating the same on its longitudinal axis.

3. In an amalgamator, a motor driven shaft, mortar supporting means, a mortar supported thereby, and a connection between said shaft and said supporting means for oscillating the mortar on its central transverse axis which passes radially through said shaft, and simultaneously reciprocating the same on its longitudinal axis.

4. In an amalgamator, a motor driven shaft, a collar, an arm extending substantially radially from said collar, means on said arm to support a capsule mortar, and a connection between said shaft and said collar for imparting an arcuate reciprocating motion to said mortar longitudi-

nally thereof, and a simultaneous oscillating motion on an axis at substantially right angles to the axis of the first said motion, and means preventing rotation of the mortar supporting means with said shaft.

5. In an amalgamator, a motor driven shaft, a collar, an arm extending substantially radially from said collar, means on said arm to support a capsule mortar, a bushing fixed to said shaft at an acute angle to the axis of said shaft, and forming a bearing for said collar, whereby an arcuate reciprocating motion is imparted to the mortar longitudinally thereof, and a simultaneous oscillation on an axis at substantially right angles to the axis of the first said motion.

10. In an amalgamator, a motor driven shaft, a bushing on said shaft fixed to rotate therewith, the longitudinal axis of said bushing being at an acute angle to the axis of said shaft, said axes intersecting substantially midway of the length of said bushing, a collar mounted on said bushing, an arm extending substantially radially from the collar, means on said arm for supporting a capsule mortar, and means to prevent rotation of the collar and arm with said shaft.

15. In an amalgamator, a motor driven shaft, a bushing on said shaft fixed to rotate therewith, the longitudinal axis of said bushing intersecting the axis of the shaft at an acute angle, a collar on said bushing, an arm extending substantially radially from said collar, means on said arm to support a capsule mortar, and resilient means attached to said collar to prevent the collar and arm from rotating with the shaft.

20. In an amalgamator, a motor driven shaft, a bushing on said shaft fixed to rotate therewith, the longitudinal axis of said bushing intersecting the axis of the shaft at an acute angle, a collar mounted on said bushing, an arm extending substantially radially from said collar and having its axis approximately intersecting the point of intersection of the axes of the shaft and bushing, means on said arm to support a capsule mortar, and resilient means attached to said collar to prevent the collar and arm from rotating with the shaft.

25. EDWARD L. CHOTT.
